CN 303950343 * 11/2016

Primary Examiner — Paula Allen Greene

(57) **CLAIM**

The ornamental design for a sound box, as shown and described.

DESCRIPTION

FIG. 1 is a perspective view of a sound box showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a front perspective view thereof, in an alternate position;

FIG. 9 is a perspective view thereof, in an alternate position; and,

FIG. 10 is a perspective view thereof, in an alternate position.

The broken lines in the figures show portions of the sound box that form no part of the claimed design.
